(57) **CLAIM**

The ornamental design for a protective shell set for game console, as shown and described.

DESCRIPTION

FIG. 1 is a front, right and top perspective view of a protective shell set for game console showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown in the figures are for the purpose of illustrating portions of the protective shell set for game console that forms no part of the claimed design.

1 Claim, 8 Drawing Sheets
